UNITED STATES PATENT OFFICE.

CLINTON E. SOMERS, OF LOS ANGELES, CALIFORNIA, ASSIGNOR TO ELMER T. GALLEY,
OF LOS ANGELES, CALIFORNIA.

DISAPPEARING-SCREEN WINDOW.

1,110,581.

Specification of Letters Patent. Patented Sept. 15, 1914.

Application filed March 12, 1913. Serial No. 753,823.

To all whom it may concern:

Be it known that I, CLINTON E. SOMERS, a citizen of the United States, residing at Los Angeles, in the county of Los Angeles and State of California, have invented new and useful Improvements in Disappearing-Screen Windows, of which the following is a specification.

This invention relates to that class of windows having one or more sashes, such as the usual top and bottom sash, and which windows are provided with disappearing screens adapted to complement said sashes, so that the screens gap the window opening created by raising or lowering the sashes.

The invention embraces certain features of novelty hereinafter particularly pointed out.

The accompanying drawings illustrate the invention.

Figure 1 is a transverse broken section through a window embracing this invention, the section being on line x^1 , Figs. 5 and 6. Fig. 2 is a broken view of a screen embracing this invention. Fig. 3 is a broken transverse section through the same screen and is on line x^3 , Fig. 2. Fig. 4 is a broken transverse section through another screen, said section being on line x^4 , Figs. 1 and 7. Fig. 5 is a broken plan section through the window on line x^5 , Figs. 1 and 7. Fig. 6 is a broken transverse section through the window on line x^6 , Figs. 1 and 7. Fig. 7 is a broken elevation of the window partly in section on line x^7 , Figs. 1 and 5. Fig. 8 is an enlarged section through a fragment of the window, and shows a portion of the bottom sash, bottom screen and means for connecting the same together. Fig. 9 is an enlarged broken section through the window on line x^9-x^{11} , Figs. 1 and 10. Fig. 10 is an enlarged view of a fragment of the window, and shows a novel shade bracket attached to same. Fig. 11 is a section through the window fragment shown in Fig. 10, and is on line x^9-x^{11} , Figs. 1 and 10. Fig. 12 shows in section a fragmentary portion of an upper and lower sash provided with a novel fly-guard. Fig. 13 is a section through a fragment of the fly-guard on line x^{13} , Fig. 1.

For purposes of clearness the usual pulley and pulley weights have been omitted from the figures, but it will be understood, of

course, that the figures are merely conventional in this respect, and that the use of the ordinary pulley and pulley weights for the sashes is optional with builder and lies within the spirit of the invention.

The window includes the usual window casing having a header 1, Fig. 1, the sill 2 and the pulley stiles 3. The parting beads 4, Figs. 1, 5 and 6, pass up along the window casing and are set in pulley stiles 3, while the mold stops 5 and blind stops 6 are attached to the window casing in the usual manner.

Between the parting beads 4 and the blind stops 6 runs the usual upper sash 7 having stiles 8, top rail 9, lock rail 10, and window pane 11. Between the parting beads 4 and the mold stops 5 runs the usual bottom sash 12 having stiles 13, upper rail 14 and bottom rail 15.

Through the header 1 is cut a header passage 16 leading to the screen chamber 17 above said header. The parting bead 4 is seen, Figs. 1 and 7, to pass up into chamber 17, and in addition to its usual functions said parting bead serves to guide an upper screen 18 in a manner more particularly described hereinafter. The screen 18 is adapted to pass down through the header passage 16, and except for certain stops, to be hereinafter described, said screen is adapted to follow the top sash in its downward course, so as to gap across the window opening created by lowering said top sash.

Through the sill 2 is cut a sill passage 19 leading to a screen chamber 20 below said sill. A bottom screen 21 is adapted to occupy a concealed position in the chamber 20, as shown in Fig. 1, and is also adapted to slide up through sill passage 19 and to follow bottom sash 12 in its upward course so as to gap across the window opening created by raising said bottom sash.

In adapting for service the type of disappearing screen window thus far described, it is a very essential prerequisite that the window be adequately equipped with means for excluding rain, snow, wind, dust, or any other meteorological inclemencies. Unless the window were thus made proof against the elements rain and wind would drive up along sill 2, beneath bottom rail 15 and down through sill passage 19 into chamber 20. The rain and wind would also drive against

parting bead 4 and stiles 13 of the lower sash, and if its force was sufficiently great said rain and wind would drive through the crack between said parting bead and stiles 5 onto the pulley stile 3, from whence a large portion would drain downward onto sill 2, through sill passage 19 and into chamber 20. The chamber 20 being bounded on one side by wall 22, which is usually made of plaster 10 and constitutes an interior wall of the house or room, it is obvious that water trapped in chamber 20 would play havoc by spoiling and staining the appearance of said plastered wall. If damage of this sort were permitted 15 to occur the use of such disappearing screen windows would become rapidly unpopular, and for the purpose of adequately protecting the system against leaks into chamber 20 this invention embraces novel 20 provisions now to be described. These provisions broadly include three features which may be used separately to advantage, but which coöperate jointly to exclude rain and snow from screen chamber 20, and which are 25 preferably used in combination. These features comprise, first, a novel weather strip for the sill; second, a parting bead cover attached to the stiles of the sash; and third, a novel bottom screen frame which may be 30 constructed so thin as to coöperate efficiently with the bottom rail for a purpose herein-after described, and which still leaves free a sufficient width of the bottom rail, which usually is narrow, so that the latter may 35 properly coöperate with said weather strip guard on the sill. Each of these features will now be described in turn.

The shape of the weather strip for the sill is best illustrated in Fig. 8, and is seen 40 to be located outside of the sill passage 19. The strip itself is preferably made of some noncorrosive metal such as zinc or galvanized iron, for instance, whereby it is possible to secure a very thin but durable structure 45 which may be adapted to operate within the exceedingly restricted space limitations encountered. The strip comprises a metal contrivance 23 extending completely across the sill from one pulley stile to the other, and 50 grooved into said sill as at 24, while nails 25 secure it in position. Near its upper edge the strip is also provided with an outwardly extending bead 26 formed, for instance, by rolling the metal over, as shown in the 55 figures, and by this provision the force of rain, dust, wind, etc., is broken and reflected back and out along the sill. In order to secure the best advantages from such a strip the bottom rail 15 of the lower sash is grooved 60 on its lower edge, as shown at 27, so as to allow said weather strip to extend up into said groove when said sash is resting on the sill. The bead 26 may rest against the outer grooved portion 28, and if the rain or dust 65 drive up along the sill beneath portion 29

of the bottom rail, said rain or dust will be arrested by said weather strip, and reflected outward by said bead so as to prevent the rain or dust from entering sill passage 19 and chamber 20.

The parting bead cover aforesaid is best shown in Fig. 6 and comprises a metal cover 30 attached to said sash and adapted to lap over the parting bead. In order that said cover may be cheaply manufactured and 70 may be efficient in its operation, it is preferably formed as shown, by a piece of metal bent substantially into a right angle, one leg of which is grooved and nailed into the sash stiles as at 31 and 32, respectively, Fig. 6, 80 while the other leg of said cover laps over and into a rabbeted or grooved portion 33 of the parting bead. By this provision the rain and dust are effectively prevented from driving through the crack between the parting bead and the sash stiles, and are consequently prevented from draining down into the sill passage 19 and chamber 20.

The screen aforesaid contains certain features of novelty, each adapted particularly for combination with the bottom rail 15 and weather strip 23. For purposes of convenience and appearance it is desirable that said screen lie directly beneath said bottom rail 15 of the lower sash, and to make this 90 feasible a screen frame, having minimum thickness coupled with strength and rigidity, is provided. The novel construction of said frame is best shown in Figs. 2, 3 and 4, and one of its faces or sides is seen to 100 comprise a metal reinforcing border 34, Fig. 4, and having a concaved inner periphery 35 forming a hook. The wire screen proper 36 extends across said frame and the border of said screen is bound and stretched 105 securely into the concaved frame portion 35 by means of wood lining fillets 37 having convex edges fitting the concaved portion. These lining fillets constitute the other face or side of said frame and extend completely 110 around same. Before their insertion into the metal reinforcing border 34 the edges of the latter stand out straight as indicated by dotted lines at 38, Fig. 4. The four wood fillets 37, one for each side of the 115 rectangular frame, are then pressed or pegged into the position shown, whereby the screen border is securely and neatly bound and contacts around the inner frame periphery as at 39, Fig. 4. The ends of the 120 four fillets 37 are each cut on a miter, as shown at 40, Fig. 2, so that they may register completely with each other when driven into position; and after being positioned the upstanding edges 38 are turned over, as 125 shown by the full lines 38', Fig. 4, whereby the parts aforesaid are locked together so as to form a very thin but substantial frame for the screen.

It will be noticed with this construction 130

that one face of the screen, which may be used for the outside, is totally metallic in its nature, and that the requisite strength and rigidity are supplied by this portion; 5 while the other face of the screen, which may be used for the inside, presents the appearance of timber, and thereby makes it possible to produce the appearance of a complete hardwood window equipment throughout. 10 This feature is important where emphasis is laid on the hardwood and ornamental finish of a room, office, etc.

In choosing the material for the outer reinforcing border of the screen a cheap, 15 non-corrosive metal, such as zinc or galvanized iron, for instance, is preferable. It is also preferable sometimes that the four sides of said metallic border be formed of four separate strips having edges cut on a 20 miter and bound to each other by the dovetail or miter lock joint as indicated at 41, Fig. 2 or 7. In this event, the abutting miter edges along with the lock joint are securely soldered, so that the whole border constitutes a rigid reinforcing agent. 25

In using a thin screen frame such as the foregoing it becomes possible to set same directly below the bottom rail 15 and to leave a sufficient portion of said bottom rail 30 free for proper coöperation with weather strip 23. This relation is shown in Figs. 1 and 8, where the upper edge of bottom screen 21 is seen set up into a recess 42 which may be considered as a portion of 35 groove 27 in the bottom rail 15 of the lower sash.

Novel provision is also made in this invention for automatically but detachably connecting the bottom sash and the bottom 40 screen together when the former is lowered down onto the latter. This provision is best understood by reference to Fig. 8 and will now be described.

Into the bottom rail 15 is formed a vertical aperture 43, and near the upper portion of same is resiliently mounted a spring latch member 44, the lower end 45 of which projects out beyond said aperture, said lower end including a latch lip 46 and a finger 50 piece 47. The upper lining fillet 37 of the screen is formed with a latched groove or socket 48, which is alined with latch lip 46, and which is automatically engaged by same when the bottom sash is lowered onto 55 the bottom screen. By this provision the lower sash and screen are normally connected to each other, so that the screen will ordinarily rise up through the sill passage 19 and along the vertical grooves 19' in the 60 stiles 3 and follow the bottom sash 12, so as to gap the window opening created when the bottom sash is raised. If it is desired, however, to detach the bottom sash from the screen, finger-piece 47 is used to withdraw 65 latch lip 46 from the latch socket 48 after

which the sash may be raised independently of the screen. By this construction for connecting the bottom sash and bottom screen together, the resiliency of the latch member 44 will always cause it to positively move 70 into the path of the socket 48 so that the latch member and socket will not fail to engage one another when they are brought into juxtaposition.

The upper screen 18 may differ somewhat 75 from the lower screen 20 as will now be described. The upper screen is adapted to be guided by the parting beads 4, and for this purpose the frame is provided with U-shaped guiding means 49, Figs. 2 and 3, bent outward from the sides of the frame substantially flush with the border 34, which means are adapted to lap over and slide along said parting beads. The upper screen is also provided with extending lips 50, Figs. 1, 5 and 80 7, which are adapted to coöperate with spring stops 51 for supporting and retaining the screen in its upper position. The lips 50 are also adapted to rest upon the upper edge of top rail 9 of the upper sash, so that 85 the top screen 18 is supported by, and is raised and lowered by, the upper sash 7. If it is desired to raise the upper screen into chamber 17 and to maintain it in its concealed position therein while the upper sash 90 is independently movable, it is merely necessary to raise the upper screen off the upper sash, as shown in Fig. 7, for instance. As the upper screen is being thus raised, lips 50 will contact with the inclined portion 52 100 of spring stops 51 and will press same toward the pulley stile 3, the supporting shoulder 53 of said stop passing into apertures 54 at this time. After lips 50 rise above shoulders 53 the spring stops will rebound into their extended positions, shown in Fig. 7, and if the screen be then released the lips 50 will rest upon shoulders 53 and will thus serve to support and retain the upper screen 105

in its concealed position. If it be later desired to lower the upper screen the spring stops 51 may be pushed toward the pulley stiles, thus releasing lips 50; or else the upper sash 7 may be raised until it contacts with lips 50. In the course of thus raising the upper sash, it will contact with the inclined portions 52 of the stops and serve to push same toward the pulley stiles in a manner obvious from the foregoing, and will thus release lips 50 from supporting shoulders 53. The lips 50 will then rest on the top rail of the upper sash and the upper screen 18 will follow the top sash in its outward course, so as to gap the window opening created by lowering said top sash. 110

In order that screen windows of the foregoing description may be rendered totally fly-proof this invention contemplates the provision of a novel fly-guard attached to 115 one of the sashes, preferably the top sash 120

as shown at 55, Fig. 1. A characteristic novelty of this fly-guard resides in a construction whereby the same is resiliently reinforced, so that it will extend across apertures of varying widths and so that time and wear will not cause same to droop and thus lose its utility as a fly-guard. The guard essentially comprises any suitable fly-proof material 56, best shown in Fig. 13, which material is reinforced by any suitable resilient means. One practical form of these means is shown as comprising resilient reinforcing wires 57 preferably embedded within the material 56. The material is also secured to a wooden strip 58, Fig. 12, for instance, which in turn may be nailed to lock rail 10 of the top sash, as shown in Fig. 12. Fly-proof material which is resiliently reinforced, and which is mounted as above, will tend constantly to extend in the direction perpendicular to the sashes, as shown in Fig. 1, and on this account will contact with the window pane of the lower sash as in Fig. 1 and will also contact with the bottom rail of the lower sash 12 as in Fig. 12 and prevent at all times the entrance of flies through the window.

In order that these windows may be rendered more practical and useful novel window shade brackets 59, Figs. 1, 5, 9, 10 and 11, for supporting a window shade and roller 60 and 61, respectively, are located in a novel position near the upper corners of the upper sash. By transferring the window shade brackets from their customary and stationary position on the window casing to a position on the sash, so that said brackets are movable with said sash, it is possible to lower the upper sash and upper screen, and by then drawing the window shade down the view of outsiders is obstructed through the window panes, while a free and unrestricted circulation of air is possible through the upper screen. In cleaning the windows, however, and for other purposes, it may be desirable to raise the bottom sash completely past the top sash, and for this reason said window shade brackets are pivotally mounted on said upper sash.

The structure essentially comprises a substantially circular base plate 62, Figs. 9, 10 and 11, said plate have an aperture 63 and being attached to the upper sash by suitable means, such as screws 64, Fig. 10, over an aperture 65 drilled into the sash. The window shade brackets 59 are provided at one end with the usual roller supporting slot or aperture 66, and at the other ends are provided with arms passed through apertures 63 of the base plate, and by means of which arms said bracket is pivotally attached to said plate. In the figures said arms are seen to comprise three in number, the central one 67 of which extends substantially parallel to the length of bracket

59, Fig. 11; while the outer two 68 of said arms extend substantially perpendicular to said bracket and have beveled edges 69, Fig. 11. The bracket is also provided with shoulders 70, Fig. 10, which prevent the bracket from slipping freely through apertures 63 in the plate 62. With this construction the bracket is partially restrained in its extended or operative position shown full in Fig. 9 and dotted in Fig. 11, by means of fingers 68, which, in this instance, abut against the base plate 62. On the other hand the bracket is partially restrained in its collapsed or folded position, shown full in Fig. 11 by means of arms 67, which, in this instance, abut against plate 62. When the sashes are to be slipped past each other, as for purposes of cleaning, etc., the window shade and roller are removed from the brackets and the brackets are pivoted into their folded position shown full in Fig. 11. In this event there is sufficient clearance between the rails of the two sashes to permit same to pass each other without interference from the folded bracket; but in order to prevent the latter from inadvertently swinging outwardly so as to be struck by the passing sash a spring means 71, Fig. 11, is provided, and this bears upon and coöperates with bevel face 69 of arms 68 in such manner as to arrest bracket 59 against an inadvertent swing as aforesaid. After the windows have been cleaned the brackets may be pivoted outward into their normal position, the window shade and roller replaced and the normal operations continued.

From the foregoing detail description it is thought that the construction and mode of operating the window embracing this invention will be clear.

I claim:—

1. In disappearing screen windows, the combination of wire screen with a frame for said screen, said frame comprising a metal reinforcing border that has a concaved inner periphery forming a hook, and wood lining fillets fitting said hook and adapted to bind said screen into the concaved periphery of said metal frame.

2. In disappearing screen windows, the combination of wire screen with a reinforced frame for said screen, said frame comprising on one side a sheet metal reinforcing portion, said metal reinforcing portion having lock miter joints near its corners, and the other side of said frame comprising wood lining fillets which coöperate with the said metal portion and serve to bind the screen onto same.

3. In disappearing screen windows, the combination of wire screen with a frame for said screen, said frame comprising a metal reinforcing border that has a concaved periphery, and wood lining fillets adapted to bind said screen into the concaved periphery

portion of said metal frame, said frame also having U-shaped guiding means bent outward from its sides.

4. In disappearing screen windows, the combination of a sill having a sill passage, a thin screen frame adapted to pass through said sill passage into a concealed position, a sash having a bottom rail that is grooved on its lower edge, a thin metal weather strip mounted on said sill and outside said sill passage, the upper edge of said screen frame and said weather strip being adapted to extend up into the groove in said bottom rail when the sash is on the sill.
- 15 5. In a window, the combination of a top and bottom sash, and a fly-guard comprising a fly proof material, and resilient means for reinforcing said material.
- 20 6. In a window, the combination of a top and bottom sash and a fly-guard, said fly-guard comprising a strip, fly proof material

attached to said strip, and resilient reinforcing wires embedded in said fly proof material.

7. In combination, wire screen, and a frame comprising a metal reinforcing border bent to form a hook and wood fillets substantially fitting said border to hold the wire screen against said hook.

8. In combination, wire screen, and a frame for the wire screen, said frame comprising a metal reinforcing border for one face of the frame and wood fillets for the other face of said frame, said border being bent to form a hook to hold said wire screen. 35

In testimony whereof, I have hereunto set my hand at Los Angeles, California, this 7th day of March, 1913.

CLINTON E. SOMERS.

In presence of—

JAMES R. TOWNSEND,
ROBERT A. STEPS.
